(57) **CLAIM**

The ornamental design for a blade for construction machinery, as shown and described.

DESCRIPTION

FIG. 1 is a front perspective view of a blade for construction machinery showing our new design;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof; and,

FIG. 7 is a left side elevational view thereof.

1 Claim, 3 Drawing Sheets*FIG. 1**FIG. 2**FIG. 3**FIG. 4****FIG. 5******FIG. 6******FIG. 7***
